ADJUSTABLE WINDOW SCREEN

Walter L. Lukaszevig, Milwaukee, Wis.

Application March 22, 1946, Serial No. 656,302

1 Claim. (Cl. 160—125)

1

This invention relates to window screens of the roller type for application to windows in such manner as to automatically cover the variable open space produced as the window sash is raised and lowered.

One object of the present invention is to provide a screen of the character described that may be readily adjusted to fit windows of various widths.

Other more specific objects and advantages will appear, expressed or implied, from the following description of an illustrative embodiment of the present invention.

In the accompanying drawings:

Figure 1 is a view in front elevation of a screen constructed in accordance with this invention and shown applied to a standard window.

Fig. 2 is a vertical sectional view thereof.

Fig. 3 is rear view looking into the screen housing.

Fig. 4 is a vertical sectional view of the screen and housing on a larger scale.

Fig. 5 is a longitudinal sectional view of one of the rollers shown in Fig. 4.

Fig. 6 is an enlarged sectional view of an edge of the screen.

The window screen selected for illustration comprises two overlapping sections 10 and 11 of screen material wound upon separate rollers 12 and 13 with their free ends removably attached by suitable means, such as screws 14, to the bottom of a lower window sash 15.

The rollers 12 and 13 are arranged one over the other in spaced, parallel, but overlapping relation within a suitable telescopic housing 16 removably attached to the window sill 17 by screws 18 or the like.

The housing shown comprises an outer section 19 of angular form having an end wall 20, and an inner section 21 of similar form slidably engaged within the outer section and having an end wall 22. Inturned flanges 23 on the outer housing section provide suitable guides for the inner section.

Both rollers 12 and 13 are hollow and spring urged in a direction to maintain the screen sections taut. As shown in Fig. 5, the upper roller 12 is supported at one end by a pin 24 carried thereby and journalled in a suitable hollow boss 25 welded or otherwise fixed to the end wall 20 of housing section 19. The other end of the roller 12 is rotatably supported on a pair of disks 26 and 27 loosely fitted therein and fixed to a rectangular bar 28 non-rotatably seated in an ear 29 carried by a suitable bracket plate 30. The

2

bracket plate 30 is removably fastened by engagement of the ends thereof beneath the in-turned edge flanges 23 of the outer housing section 19. A coiled spring 31 engaged with the disk 27 and roller 12 urges the roller to rotate in the manner above described. The roller 12 is thus supported by and within the outer housing section 19 wholly independently of the inner section 21.

10 In a similar manner the other lower roller 13 is supported by and within the inner housing section 21 independently of the outer section 19. That is to say, the lower roller 13 is supported at one end by a pin 32 journalled in an ear 33 carried by the inner end of the housing section 21 and at the other end by a rectangular bar non-rotatably seated in a hollow boss 35 carried by the end wall 22 of the inner housing member.

By winding the screen sections 10 and 11 on 20 separate rollers 12 and 13 arranged one above the other in the manner shown and described, it is possible to maintain a tight, firm, face-to-face contact between the overlapping portions of the screen sections as the window sash is raised and lowered. By this arrangement it is possible to eliminate the gap-producing bulges that would inevitably result if attempt were made to wind both screen sections in overlapping relation on a single roller. Also, by virtue of this arrangement 30 and the fact that the rollers 12 and 13 are separately carried in their respective housing sections, it is a simple matter to adjust the housing sections telescopically to fit windows of various widths, the rollers and screen sections carried 35 thereby being free to automatically adjust themselves in accordance with any adjustment of the housing sections.

Various changes may be made in the embodiment of the invention hereinabove specifically 40 described without departing from or sacrificing the advantages of the invention as defined in the appended claim.

I claim:

A window screen comprising a longitudinally 45 adjustable housing having a pair of inner and outer telescopic sections lengthwise adjustable relative to each other, a pair of longitudinally overlapping rollers extending lengthwise of and within said housing, a pair of overlapping flexible screen sections respectively wound on said rollers, means at the opposite ends of said inner housing section for supporting one of said rollers, means at the outer end of said outer housing section for supporting one end of the other of 50 said rollers, a plate disposed within said inner

housing section and secured at its opposite extremities to said outer housing section, and means on said plate for supporting the opposite end of said last mentioned roller.

WALTER L. LUKASZEVIG.
